UNITED STATES PATENT OFFICE.

CLAUS J. WERNER CLASEN, OF DAVENPORT, IOWA, ASSIGNOR TO THE BETTENDORF COMPANY, OF BETTENDORF, IOWA, A CORPORATION OF IOWA.

UNDERFRAME.

1,100,419.

Specification of Letters Patent. Patented June 16, 1914.

Application filed March 12, 1913. Serial No. 753,783.

To all whom it may concern:

Be it known that I, CLAUS J. WERNER CLASEN, a citizen of the United States of America, and resident of Davenport, Scott county, Iowa, have invented a certain new and useful Improvement in Underframes, of which the following is a specification.

My invention relates to the underframes of railway cars and especially to that type of underframes in which the center sill extends continuously from end to end of the car, and is directed more particularly to the improved formation and application of the draft arms and body bolsters to the center sill.

The main object of my invention is to provide means of attaching the draft rigging to a continuously extended center sill in a manner that will leave free and unobstructed the upper portion of the web and all of the upper edge or flange of the center sill by any part or portion of the draft rigging in the vicinity of its connection thereto.

Another object of the invention is to provide a strong and substantial union of the center sill and draft arms where intersected by the body bolster.

These and other objects which will hereinafter appear, are attained by the structure illustrated in the accompanying drawings, in which—

Figure 1. is a side elevation, partly in section, of the side of a car at one end, provided with a single I beam center sill and showing my improved draft arms in place. Fig. 2. is a vertical cross section of a portion of a car taken on line C—D of Fig. 1. Fig. 3. is a plan view of the end of the single I beam center sill, showing in dotted lines the manner of applying the draft arms and bolster thereto. Fig. 4. is a vertical cross section of the center sill and draft arms taken on line A—B of Fig. 3.

Similar numerals refer to similar parts throughout the several views.

While a fragmentary view of one end only of the car is shown, it is to be understood that the other end is a duplicate of the end shown and that the center sill 1, preferably an I beam, extends continuously from end sill 2 to a similar end sill at the other end. The lower flange of this I beam center sill

and a portion of the web are coped off or cut away for some distance back from each end as indicated by the dotted line E. F. G. in Fig. 1, forming a recess or indent. Located in the pocket thus formed are the draft arms 3—3, one on each side of the center sill web, forming a housing or supporting structure for the draft gear mechanism and through which the buffing shocks and pulling strains are transmitted to the center sill. These draft arms are riveted to the web of the center sill along its severed edge through the medium of the vertical flanges 3^a made integral therewith. From the lower edge of these flanges 3^a the walls of the draft arms, for the greater portion of their length, extend laterally for a short distance and thence downwardly, thus forming a passage way for the upper limb of the draw-bar yoke. These walls again extend laterally for another short distance and thence downwardly, terminating in the outwardly projecting flanges 3^b, thus forming the housing proper for the reception of the draft gear mechanism.

At the rear end the walls of the draft arms are bent or brought in toward and closely embrace the web of the center sill and extend on a distance past the point of intersection of the body bolster 4 and the center sill. The flanges 3^b lap over and are riveted to the lower flange of the center sill. Registering with and following the contour of the H shaped opening in the center sill through which body bolster 4 passes, are the flanges 3^c extending a distance laterally from the draft arms and made integral therewith. These laterally extending flanges or gussets closely embrace all surfaces of the body bolster where in contact with it and are usually riveted to the vertical web of the bolster. The forward end 3^d of the draft arms extend beyond the end sill 2 to receive the striking plate 5. In the lower part of the outer end the draw-bar carry iron 6 is fitted and held in position by bolt 7. The outer end of the vertical flange 3^a is increased in height and terminates in the laterally extending flange 3^b by which it is secured to the end sill 2.

It is to be understood that the laterally extending flanges or gussets 3^c could be made separable from and riveted to the outer face

of the draft arms 3; and these draft arms could be cast integral without departing from the spirit of my invention.

What I claim as new is—

- 5 1. In an underframe for cars, end sills, a center sill extending from end sill to end sill, body bolsters, and draft arms the rear ends of which closely embrace the center sill and extend past the intersecting planes of the 10 body bolsters.
2. In an underframe for cars, end sills, a center sill extending from end sill to end sill, and draft arms closely embracing and secured to the said center sill, in the intersecting 15 planes of the body bolsters.
3. In an underframe for cars, end sills, a single I beam center sill extending from end sill to end sill, and cast metal draft arms closely embracing and secured to the said 20 center sill in the intersecting planes of the body bolsters.
4. In an underframe for cars, a center sill provided with longitudinal indents at each end, draft arms occupying said indents, and 25 the rear ends of which extend past the intersecting planes of the body bolsters.
5. In an underframe for cars, a center sill provided with longitudinal indents at each end, draft arms occupying said indents and 30 lapping the web of the center sill past the intersecting planes of the body bolsters.
6. In an underframe for cars, center sills provided with longitudinal indents at each end, draft arms occupying said indents, the 35 rear ends of which extend past the intersecting planes of the body bolsters, said center sills and draft arms having openings in their lapped portions for the passage of the said body bolsters.
- 40 7. In an underframe for cars, center sills provided with longitudinal indents at each end, draft arms occupying said indents and lapping the web of said center sills past the intersecting planes of the body bolsters, said center sills and draft arms having parts of their lapping portions displaced to permit the passage of said body bolsters.
8. In an underframe for cars, a flanged beam center sill having recesses formed by 45 removing the lower flange and a portion of its vertical web for a distance back from each end, draft arms occupying said recesses and secured to and lapping the web of said center sill past the intersecting planes of the body bolsters.
9. In an underframe for cars, a flanged beam center sill having recesses formed by 50 removing the lower flange and a portion of its vertical web, for a distance back from each end, draft arms occupying said recesses and secured to and lapping the web of said center sill past the intersecting plane of the body bolster, and having openings in 55
- their lapped portions for the passage therethrough of said body bolster. 65
10. In an underframe for cars, end sills, an I beam center sill extending from end sill to end sill, having recesses formed by removing the lower flange and a portion of the vertical web for a distance back from each end; draft arms occupying said recess and secured to and lapping the web of the center sill past the intersecting planes of the body bolsters; and having openings in 70 their lapped portions for the passage therethrough of said body bolsters. 75
11. In an underframe for cars, end sills, body bolsters, a center sill provided with longitudinal indents at each end, draft arms occupying said indents and lapping the web of the center sill past the intersecting plane of the body bolster, flanges extending laterally from said draft arms forming gussets. 80
12. In an underframe for cars, end sills, body bolsters, a center sill provided with longitudinal indents at each end; draft arms filling said indents and lapping the web of the center sill past the intersection plane of the body bolster; flanges extending laterally from and made integral with said draft arms forming gussets closely embracing the said body bolsters. 85
13. In an underframe for cars, end sills, a single metallic beam having its ends reduced vertically and secured to the end sills, draft arms secured to the beam in the reduced portion and to the end sill and lapping the said metallic beam past the intersecting planes of the body bolsters and secured 90 thereto. 100
14. In an underframe for cars, end sills, a single flanged beam center sill extending from end sill to end sill and secured thereto, longitudinal indents extending from the ends of said center sill toward its center of length, a draft member in said indent secured to said center sill and end sill and extending past the intersecting plane of the body bolster. 110
15. In an underframe for cars, end sills, a single flanged beam center sill having its ends reduced vertically and secured to the end sills, draft arms secured to the center sill in the reduced portion and to the end 115 sill, the forward end of said draft arms extending beyond said end sill and the rear end lapping the web of said center sill past the intersecting plane of the body bolster and secured thereto. 120
16. In an underframe for cars, end sills, a single flanged beam center sill extending from end sill to end sill and secured thereto, longitudinal indents formed in the ends of said center sill, draft arms secured to the center sill in said longitudinal indents and 125

to the end sill, the forward end of said draft arms extended beyond said end sill and provided with a striking plate and draw-bar carry iron, the rear end of said draft arms lapping the web of said center sill past the intersecting plane of the body bolster and secured thereto.

Signed by me at Davenport, Iowa, this 10th day of March 1913.

CLAUS J. WERNER CLASEN.
